UNITED STATES PATENT OFFICE.

WILLIAM DUNLOP FAULKNER, OF CLAYTON, MANCHESTER, ENGLAND.

WEFT-CONTROLLER FOR AUTOMATIC LOOMS.

968,649.

Specification of Letters Patent. Patented Aug. 30, 1910.

Application filed March 2, 1909. Serial No. 480,818.

To all whom it may concern:

Be it known that I, WILLIAM DUNLOP FAULKNER, a subject of the King of Great Britain and Ireland, and resident of Clayton, Manchester, England, have invented certain new and useful Improvements in or Relating to Weft-Controllers for Automatic Looms, of which the following is a specification.

10 These improvements refer to weft controllers for automatic looms and have for their object to provide means whereby, when the weft fails, a fresh shuttle will be inserted, and whereby, when this shuttle sticks or 15 otherwise fails to complete a pick, the loom is stopped, thereby allowing of the continuous working of the loom so long as there is a supply of weft without fear of the shuttle-holding magazine becoming rapidly emptied 20 by reason of a fault in the shuttle box or the picker mechanism.

The invention is illustrated upon the accompanying drawing, whereon—

Figure 1 illustrates a side elevation, and 25 Fig. 2 a plan of the improved apparatus as it appears when the "feeler" is about to operate the reshutting mechanism. Fig. 3 illustrates a further side view of the apparatus but as it appears immediately after a 30 new shuttle has been inserted, and before the loom slay makes its next forward movement. Fig. 4 illustrates another side view of the apparatus as it appears when stopping the loom. Figs. 5 and 6 illustrate elevation and 35 plan respectively of sufficient of a loom to illustrate the application thereto of this invention.

According to the invention, instead of using a special feeler for operating the remaining 40 reshutting mechanism, use is made of the ordinary weft fork for controlling and actuating the reshutting mechanism, the weft fork, when operated on by the usual hammer lever, transmitting its movement to the 45 reshutting lever arm *a* through a pivoted bar or plate *b*, which, at one end, is connected to the said lever arm, and at the other end is shouldered down and by such shoulder rests upon a stud or pin *c* carried by 50 the weft-fork rod. The cross rod *a'* upon which the lever arm *a* is mounted is the operative member of any known type of mechanism which, on being rotated, permits of an empty or faulty shuttle being 55 ejected and a newly filled shuttle inserted in the shuttle box. For stopping the loom

should the weft fail or the shuttle stick, use is also made of a disk wheel *d*, carried by a bracket or supporting arm secured to the frame or breast beam of the loom whereon, about its center, is mounted a lever arm *e*, the free end of which is supported by a small boss *f* on the disk wheel. Such disk wheel has an extension *d'* giving it practically the form of an ellipse, and by 60 such extension it bears normally against the stud *c* on the weft-fork rod. In the periphery of the disk wheel *d* is a notch *d''*, and above the wheel is one arm of a lever *g* which is normally horizontal or nearly so, 65 while the other arm is inclined downwardly and lies adjacent to a pin *h* on the hammer lever. Upon the disk wheel *d* is a further pin *i*, and upon the said bar or plate *b* is a curved, cam-like projection *b'* in the path of 70 which lies the pin *i*.

When the weft fails, the hammer lever moves the bar or plate *b* in the direction of the arrow *x* and brings about the reshutting of the loom. At the same time the pin *c* 75 meets and rotates the disk wheel in the direction of the arrow *y* until the cranked end of the lever *g* (see Fig. 2) falls in front of the notch *d''*. In being thus rotated the disk wheel lowers the lever arm *e* which 80 may fall upon the pin *c*. On the plate *b* making its return movement in the usual way the projection *b'* rides on the pin *i* on the disk wheel *d* and the shoulder of the plate *b* is thereby raised clear of the pin *c* 85 on the weft fork carrying rod. Should the weft again fail immediately the new shuttle has been inserted, the pin *c* on the weft fork carrying rod then acts on the lever arm *e* on the 90 and thereby causes a further rotation of the disk wheel *d* in the direction of the arrow *y* until the extension *d'* presses against the usual stopping lever *j*, see Fig. 4, and stops the loom. Should, however, the weft not 95 again fail as suggested, the pin *h* on the hammer lever strikes the depending arm of the lever *g*, releases the disk wheel *d*, and thus allows the parts, under their normal 100 balance or under the influence of the weight *k* (or a spring) to resume their normal position. To release the cloth "take-up" roller when there is a false pick, the axis of the disk wheel may be fitted with a further lever arm or finger, which, on the disk wheel being 105 rotated to stop the loom, will serve to act upon the cloth take-up roller retaining lever or pawl and hold it clear of the usual 110

take-up wheel. By the provision of a small latch, the plate *b* may be held normally elevated and the lever arm normally depressed, and thereby stop the loom each time the weft fails.

5 What I claim is:—

1. In weft controllers for automatic looms, and in combination with the weft replenishing mechanism, a bar or plate connected to 10 the reshttling lever arm, a weft fork carrying rod, a pin or stud on said rod, a disk wheel with pin thereon for supporting the bar or plate in line with the pin or stud on the weft fork carrying rod or for holding it 15 clear of such pin or stud, substantially as herein set forth.

2. In weft controllers for automatic looms, and in combination with the weft replenishing mechanism, a bar or plate connected to 20 the reshttling lever arm a weft fork carrying rod with pin or stud thereon, a disk wheel and pin, a lever arm mounted upon said disk wheel and working in conjunction

therewith, an extension piece on the disk wheel which presses against the stopping 25 lever to stop the loom, substantially as herein set forth.

3. In weft controllers for automatic looms, and in combination with the weft replenishing mechanism, a bar or plate connected to 30 the reshttling lever arm, a weft fork carrying rod with a pin or stud thereon, a disk stud and pin, a lever arm mounted upon said disk wheel, an extension piece on the disk wheel, a hammer lever with pin mounted 35 thereon, a lever with depending arm which is operated by the pin on the hammer lever to release the disk wheel, substantially as herein set forth.

In witness whereof I have hereunto set 40 my hand in the presence of two witnesses.

WILLIAM DUNLOP FAULKNER.
